UNITED STATES PATENT OFFICE.

BENJAMIN F. LUNG, OF BENZONIA, MICHIGAN.

CAN-OPENER.

1,319,597.

Specification of Letters Patent. Patented Oct. 21, 1919.

Application filed August 16, 1918. Serial No. 250,181.

To all whom it may concern:

Be it known that I, BENJAMIN F. LUNG, a citizen of the United States, residing at Benzonia, in the county of Benzie and 5 State of Michigan, have invented new and useful Improvements in Can-Openers, of which the following a specification.

This invention relates to a can and bottle opener, the object in view being to provide 10 a hand operated device which is especially convenient and effective for the purpose stated, enabling a clean cut of any desired length to be made either in the top or bottom of a can or in and around the side wall 15 of the can.

While the improved device is adapted for opening small cans it is especially adapted for opening cans of large sizes, as the work may be done with ease and 20 rapidity, leaving a clean edged cut.

Another advantage of the device resides in the fact that the cut is made outwardly so as to eject the small particles of tin or other material which are removed from the 25 edges of the cut during the cutting operation.

With the above and other objects in view, the invention consists in the construction, combination and arrangement of parts, as 30 herein described, illustrated and claimed.

In the accompanying drawing:

Figure 1 is a perspective view of the opener.

Fig. 2 is a plan view of the body of the 35 device showing the formation of the blades and other parts thereof.

Fig. 3 is a plan view of the handle with the fulcrum piece attached.

Fig. 4 is a cross-section on the line 4-4 40 of Fig. 3, showing the fulcrum piece in elevation.

The improved opener comprises a loop handle 1, or the equivalent thereof, composed of a strip of metal or other suitable 45 material of any suitable length bent or formed into the form shown in Fig. 3.

2 designates the body of the opener which is formed of sheet steel or other suitable material and fastened between the 50 parallel portions 3 of the handle by means of rivets 4 or the equivalent thereof, the body 2 being thus rigidly fastened to the handle. The handle is provided with outwardly 55 end portions 5 and secured thereto by fastening means 6 is a transversely oblong fulcrum piece 7, the working edge of

which is preferably serrated as shown at 8. The fulcrum piece 3 is formed with a notch or slot 9 to straddle one of the blades of the device as shown.

The body 2 comprises a blade 10 of ogee-shape and another blade 11 which is curvilinear or C-shape. In addition to the blades 10 and 11, there is a short pointed combination can and bottle opening tang 12, the outer extremity of which is pointed as shown at 13, adapted for opening cans containing liquid only, milk or oil, for example, in which case frequently a small opening is desired. In using point 13, with 70 the can in the upright position, the opener is placed in a practically horizontal position, point 13 being driven through the end wall of the can, adjacent to the edge of the latter. After the point has been inserted through the can, the opener is 75 pressed firmly downward and the handle is moved in a circular direction, thus causing point 13 to act as a pivot, and in this manner the opening may be made any size 80 up to the width of the tang. Said tang also has adjacent to the base thereof, a lifting point or hook 14 adapted to engage the underside of the rim of a bottle cap for example, and pry said cap off the bottle, 85 the fulcrum piece 7 resting upon the cap at a point diametrically opposite that point engaged by the hook 14.

The blade 10 is formed with a reversely extending can puncturing point 15, and the 90 blade 11 is likewise formed with a reversely extending can puncturing point 16, the points 15 and 16 being used to primarily puncture or penetrate the can and thereby enable the respective blades to be used for 95 finishing the cutting operation.

In using the blade 10, with the can in a horizontal position, the opener is placed in a substantially vertical position, and the point 15 is forced through the side wall of 100 the can adjacent to the edge thereof and about one-half to one inch in front of the seam extending longitudinally of the side wall of the can. After the point 15 is well inserted, the handle is pressed downwardly 105 or toward the can thereby causing blade 10 to cut backwardly in the side wall of the can as far as the seam and parallel to adjacent end thereof. The blade 10 is then moved inwardly as far as it will go and an upward 110 cut is formed by raising the handle of the device. The operation just referred to is

continued except when completing near seam better results are obtained by using the blade near the point. If the can contains liquid, the cut may be made while the can 5 is standing in the upright position after the first operation of inserting the point 15 has been effected.

When using blade 11, with the can in an upright position, the device is started in a 10 practically vertical position, the point 16 being driven through end wall of can adjacent to the edge of the latter. After the point has been inserted through the can, the handle is pressed firmly downward, thus 15 causing the blade 11 to cut backwardly. The device is then restored to a substantially upright position and the handle pressed firmly downward while the fulcrum piece is held in engagement with the edge of the can. 20 This causes the blade 11 to form an upward and forward cut. The operation just referred to is continued, always moving the blade forwardly to the end of the previous cut, after each operation until the top of the 25 can has been completely removed. After the primary puncturing process has been effected, it will be observed that the opener always cuts upwardly or outwardly, thereby giving a tendency to eject or to throw out 30 the loose particles of metal or other material.

The blade 11 is provided with a serrated

portion 19 on the convex side extending from a point near and below the junction of blades 10 and 11, to a point below fulcrum piece 7, and near the upper cutting extremity of 35 blade 11, which acts as fulcrum for blade 10, and rests upon a point above and in front of where the cutting edge of blade 10 engages with the can, and prevents slipping during 40 the cutting operation.

I claim:—

The combination of a handle, and a can-opening member fastened thereto and embodying two cutting blades one of which is 45 ogee shaped lying and disposed laterally of the handle and formed with a reversely curved and pointed end portion, the other blade being C-shaped and projecting from the end of the handle and also having a 50 reversely curved and pointed end portion, the first named blade having a concaved cutting edge and the second named blade having a convex cutting edge opposed thereto and serrated for a portion of its length, said cutting edges being in spaced relation to each 55 other and the end portion of the first named blade being extended beyond the end of the handle in overlapping but spaced relation to the second named blade.

In testimony whereof I affix my signature. 60

BENJAMIN F. LUNG.
